ATTORNEY

UNITED STATES PATENT OFFICE.

BENJAMIN J. HUDSON, OF WILSEY, KANSAS.

CLAMPING DEVICE.

1,241,629.

Specification of Letters Patent.

Patented Oct. 2, 1917.

Application filed June 27, 1916. Serial No. 106,235.

To all whom it may concern:

Be it known that I, BENJAMIN J. HUDSON, a citizen of the United States, residing at Wilsey, in the county of Morris and State 5 of Kansas, have invented certain new and useful Improvements in Clamping Devices, of which the following is a specification:

My invention relates to a clamping device for securing work, especially wheels to a 10 stand or support, and especially aims to provide an article for this purpose which may be operated quickly and will enable the present block and screw devices to be dispensed with and the same end that they 15 accomplish to be effected in a much shorter period of time.

Further I aim to provide an element to extend through the wheel and serve as an anchor for a clamping device to engage the 20 wheel.

As well, I aim to provide a dog to frictionally engage the anchor and a means to move the dog into and maintain it in biting relation with the anchor.

Further I aim to provide a link to pivot the dog through a fastening means with the pivot adapted to be moved with the latter to and beyond the vertical to fasten the dog.

With the above, and additional objects, such as will hereinafter appear, in view, the invention has been embodied in one preferred form as hereinafter described and illustrated in accompanying drawings.

In said drawings:

Figure 1 is a view showing my device in side elevation and in use;

Fig. 2 is a vertical sectional view through my improved device with the actuating handle omitted and with the addition of the anchor member;

Fig. 3 is a plan view of the cam member employed;

Fig. 4 is a view of the blank from which the cam member is formed, and

Fig. 5 is a detail plan view of one of the links.

While the invention is capable of general use as a work clamp, yet it is specifically adapted for use in connection with a wheel and therefore for the purposes of illustration a wheel hub is shown at 6 supported from a work table or stand 7. From the center of the table 7 is a rod or anchor 8 extending upwardly above it and is pivoted at its lower end as at 9 to the floor or

other convenient means. This anchor 8 extends through the axle opening of the hub and above it and also extends through one or more protecting plates or blocks 9 which 60 may rest on the upper end of the hub 6.

Referring specifically to the clamping device proper, 10 designates a dog which has an opening 11 therethrough and through which the anchor or rod 8 passes. Links 65 12 are employed and may be of any suitable construction but are preferably formed as shown in Fig. 5. A strip of material from which the links are made is bent upon itself and adjacent the closed end a pivot 70 pin 13 passes therethrough and also through the dog 10. At the free ends, the links are separated so as to receive between them side or cam walls 14 of a fastening member generally designated 15. Pivot pins 16 pass 75 through the walls 14 and the links adjacent their free ends. The fastening member 15 may be stamped from a flat blank as illustrated in Fig. 4 and then bent into the shape shown in Fig. 3 where the walls 14 are separated and parallel, being bridged by a connecting wall 16 and formed into a socket 17 which receives an actuating handle 18^a of any suitable construction and which may be fastened in place by any suitable means. 80 An abutment member in the form of a curved rod 18 may join the cam walls 14. The cam edge of the walls 14 is indicated at 19.

When the work is to be clamped to the 90 support it is positioned as shown in Fig. 1 whereupon the improved clamping device is also positioned as shown in full lines in the said figure. The anchor 8 passes through the opening 11 and the pivots 16' are disposed to the left of the anchor 8 and the handle or lever 18^a is elevated. The anchor 8 may be in engagement with the abutment member 18. Upon lever 18 being depressed, the cam edges 19 will engage the protecting 95 blocks 9 and the handle will be depressed to a substantially horizontal position so as to bring the pivot 16' to the right of the anchor 8 and diagonally opposite edges of the dog 10 of the opening 11 into biting 100 engagement with the anchor or rod 8. Since the pivots 16 are now to the right of a vertical line, the device will remain in this clamped position until the lever 18^a is again raised to the full line position shown in 110 Fig. 1. The operation of the device may be accomplished in a short period of time and

is readily adaptable to work of varying thicknesses since the dog and device as a whole is freely movable longitudinally of the anchor and coöperate therewith at any 5 location.

Since merely the preferred embodiment of the device has been illustrated and described, it is to be understood that changes in the details of construction may be 10 sorted to within the spirit and scope of the invention.

I claim:

1. In a clamping device, the combination with an anchor rod, of a dog having a pinching engagement with the anchor rod, a cam having spaced walls to permit the passage of the anchor rod therethrough, the cam including a handle projecting therefrom, an abutment between the walls adapted to engage the anchor rod on one side, and connecting links between the free ends of the dog and the cam at the other side of the rod.
2. In a clamping device, the combination with an anchor rod, of a handled cam hav-

ing spaced walls adapted to receive the 25 anchor therebetween, a curved abutment secured to the side walls of the cam and being adapted to engage the anchor, link members fulcrumed to the side walls of the cam the fulcrumed points of the links being normally at one side of the anchor, and a dog 30 fulcrumed at the upper ends of the links said dog having an opening arranged to permit passage of the anchor rod therethrough, the diagonally opposite edges of 35 said opening being adapted to engage and bite into the anchor rod upon rotation of the cam, said dog and cam being locked to said rotated position by the displacement of the link fulcrums to the other side of the 40 anchor rod.

In testimony whereof I affix my signature in presence of two witnesses.

BENJAMIN J. HUDSON.
